CARTON

Walter J. Byrd, Chatham, N. J., assignor to Johnson & Johnson, a corporation of New Jersey

Application January 28, 1947, Serial No. 724,897

4 Claims. (CL 206—59)

1

This invention relates to packaging and more particularly to a package or carton especially suitable for packaging and dispensing continuous strips or webs of materials as surgical dressings. One of the objects of this invention is to provide an improved dustproof carton of this type, that is, preferably one that will retain the contents free from dust and other foreign matter, maintain sterile contents in such condition until the carton is opened, facilitate dispensing the contents, and thereafter maintain the undispensed contents substantially free from dirt and contamination.

Further objects and resulting advantages will become apparent from the detailed description of one embodiment of this invention given in connection with the following drawings in which:

Fig. 1 is a perspective view of the package illustrating one embodiment of this invention.

Fig. 2 is a similar view illustrating the contents being dispensed.

Fig. 3 is an enlarged sectional view of the upper end of the package illustrating the positioning of the end and side flaps.

Referring more particularly to the drawings, it will be observed that this invention has been illustrated in the form of a carton particularly suitable for packaging and dispensing a roll of surgical gauze. For this purpose, the carton indicated generally by the reference character 1 is rectangular in shape and of suitable internal dimensions to receive the desired size of roll of gauze 2.

In general, the carton comprises side, or front and rear walls 3 and 5 which terminate at one end in the usual bottom flaps (not shown) and end walls 7 and 8 which also terminate in the usual bottom flaps (not shown). The bottom flaps are turned inwardly, overlapped and glued as is customary in packages of this type to seal the bottom of the carton.

The end walls 7 and 8 terminate at their other ends (the top) in end flaps 9 and 10 of such lengths so that when folded inwardly toward each other they leave a slot 11 through which the discharge end of the gauze may be threaded and led outwardly. The front or side wall 3 is provided with a top side flap 12 which is normally folded inwardly and over the upper end flaps 9 and 10 and also overlies the withdrawal or outwardly threaded end of the gauze. The other or rear side wall 5 is also provided with a top side flap 13 which overlies flap 12 and is glued thereto to completely seal the carton.

The top flap 13 is provided with an extending

10 tongue 14 which is folded under one end of the side flap 12 when the carton is closed. The discharged end 15 of the roll of gauze is stapled as at 16 or otherwise fastened to the free end of this undeturned tongue 14 so as to cause the gauze to be withdrawn with the tongue. To facilitate removal of the tongue and withdrawal of the gauze, the upper flap 13 is provided with score lines 17 or is otherwise weakened to provide a tear out portion 18.

When it is desired to withdraw or dispense gauze from the sealed carton, it is only necessary to break out the portion 18 along the scored lines 17 and pull this portion outwardly. This will withdraw the desired portion of the gauze or other material which has been secured to the inturned tongue 14 through the slot 11 and between flaps 10 and 12. The desired portion or length of gauze may then be cut off leaving a sufficient end of gauze to grasp when more material is desired.

From the foregoing, it will be seen that there has been provided a carton which is substantially dust and dirt proof, which will retain the contents in sterilized condition until the carton has been opened and which provides for ready removal and dispensing of the contents of the package when desired without exposing more than a minimum of the contents at any time. It will be apparent to those skilled in the art that minor variations may be made in details of construction without departing from the spirit and scope of this invention as defined in the appended claims.

35 I claim as my invention:

1. A carton for containing and dispensing a continuous strip of material contained therein, said carton comprising side and end walls terminating at one end in bottom flaps secured 40 together to close the bottom of the carton, said end walls terminating at their other ends in a pair of top end flaps folded toward each other and being of such lengths that when so folded they provide a slot for the passage of said material, said side walls terminating at their other ends in a pair of overlapping top side flaps, and a tongue formed as an integral part of and detachable from said one of said side flaps, said tongue being secured to the discharge end of said 45 material whereby said material may be dispensed by detaching and withdrawing said tongue.

2. A carton for containing and dispensing a continuous strip of material contained therein, said carton comprising side and end walls terminating at one of their ends in bottom flaps

secured together to close the bottom of the carton, said end walls terminating at their other ends in a pair of top end flaps folded toward each other and being of such lengths that when so folded they provide a slot for the passage of said material, said side walls terminating at their other ends in a pair of overlapping top side flaps, and a tongue formed as an integral part of and detachable from the outermost of said top side flaps, said tongue being secured to the discharge end of said material whereby said material may be dispensed by detaching and withdrawing said tongue.

3. A carton for containing and dispensing a continuous strip of material contained therein, said carton comprising side and end walls terminating at one of their ends in bottom flaps secured together to close the bottom of the carton, said end walls terminating at their other ends in a pair of top end flaps folded toward each other and being of such lengths that when so folded they provide a slot for the passage of said material, said side walls terminating at their other ends in a pair of overlapping top side flaps, and a tongue formed as an integral part of and detachable from the outermost of said top side flaps, said tongue extending beneath the lowermost of said top side flaps and being secured to the discharge end of said material whereby said

material may be dispensed by detaching and withdrawing said tongue.

4. A carton for containing and dispensing a continuous strip of material contained therein, said carton comprising side and end walls terminating at one of their ends in bottom flaps secured together to close the bottom of said carton, said end walls terminating at their other ends in a pair of top end flaps folded toward each other and being of such lengths that when so folded they provide a slot for the passage of said material, said side walls terminating at their other ends in a pair of overlapping top side flaps, a tongue extending from the outermost of said top side flaps, said tongue being secured to the discharge end of said material, and lines of weakness in said outermost top side flap facilitating detachment of said tongue whereby said material may be dispensed by detaching and withdrawing said tongue.
